UNITED STATES PATENT OFFICE.

EDMUND SPENSER TIDDEMAN, OF GREAT NELMES, HORNCHURCH, ENGLAND, AS-
SIGNOR TO W. R. SYKES INTERLOCKING SIGNAL COMPANY LIMITED, OF CLAPHAM,
LONDON, ENGLAND.

RAILWAY SIGNALING.

Application filed July 24, 1920. Serial No. 398,788.

(GRANTED UNDER THE PROVISIONS OF THE ACT OF MARCH 3, 1921, 41 STAT. L., 1313.)

To all whom it may concern:

Be it known that I, EDMUND SPENSER TIDDEMAN, of Wood End, Great Nelmes, Hornchurch, in the county of Essex, England, a subject of the King of Great Britain, have invented certain new and useful Improvements in Railway Signaling, (for which I have filed an application in England, March 19th, 1919, Patent No. 135,-
10 743), of which the following is a specification.

This invention relates to apparatus for automatically controlling railway traffic and more particularly to that type of such apparatus which includes an electrically conductive track-ramp and a co-operating plunger and shoe carried by the locomotive or other vehicle whereby the operation of the brakes is automatically controlled in accordance with the electrical condition of the ramp as governed by the position of a co-operating road signal.

The object of the invention is to provide an improved track layout including means for enabling a locomotive to be backed or, in some cases, run forward over a ramp, notwithstanding that the signal to which such ramp appertains happens to be standing at "line blocked," without the brakes being in consequence applied; it being frequently desirable that such freedom should be afforded when, for example, shunting operations are being performed.

An example of the present invention, as applied to a single-line railway, is illustrated diagrammatically in the accompanying drawings, wherein Figures 1 and 2 show the state of the electrical connections when the road signal, with which the track ramp is adapted to co-operate, is standing at "line clear" and "line blocked" respectively; the track-ramp being unoccupied by a train.

In systems of the kind to which the present invention relates the locomotive (or other vehicle) 17, carries an upright plunger a fitted to slide vertically through a guide c and tending (under the stress of a spring, not shown) to assume a bottom limit position wherein an electrically-conductive shoe 16 at the lower extremity of the plunger can so encounter a track-ramp as to be raised thereby during the passage of the locomo-

tive over the ramp. The shoe 16 is in permanent electrical connection (as for example, through the plunger a and a stationary contact-piece c^1 with which the plunger is in constant frictional contact) with one pole of the winding of an electromagnet s , hereinafter termed the "locomotive electromagnet", also with one polar terminal of an electric bell w , and further with one pole of the winding of a polarized relay u , hereinafter referred to as the "locomotive polarized relay", the electromagnet s , bell w , and relay u being all carried by the locomotive 17. The other pole of the winding of the electromagnet s and the other pole of the winding of the relay u are both permanently earthed at t , whilst the other polar terminal of the bell w is permanently connected to the switch-tongue v of the relay u .

The shoe 16, as it passes in either direction over the track-ramp, is always mechanically raised thereby, and therefore thrusts upwards the plunger a , to a corresponding extent, it being understood that the extent of such upward movement must exceed a predetermined limit in order to bring about the application of the brakes. If on the one hand, when the plunger a is raised, the electromagnet s happens to be de-energized owing to the ramp being electrically "dead" in consequence of the road signal standing at "line blocked," the rise of the plunger a will be permitted to bring about, by mechanical means provided on the locomotive 17 but not shown, the application of the brakes and the giving of a danger signal in the cab of the locomotive. If, on the other hand, when the plunger a is raised, the electromagnet s happens to be energized owing to the ramp being electrically charged with current of either polarity in consequence of the road signal standing at "line clear," the electromagnet will attract its armature v and, by means not shown, will prevent the application of the brakes and the giving of a danger signal in the cab.

The track-ramps which (on a single-line railway, as in the example shown) control traffic in opposite directions are adapted to be charged with current of different polarities respectively, the polarities of the

respective ramps being such that, during the passage of the shoe 16 over a track-ramp appertaining to any road signal which controls traffic in the direction wherein the 5 train is proceeding forwards, the bell *w* will be rung in consequence of the energization of the polarized relay *u* having for effect to move the switch-tongue *v* from the normal inoperative position shown, to the 10 position wherein, by bearing against a permanently-earthed contact *v*₁, this tongue completes the circuit of the bell, the tongue *v* remaining, however, unaffected when the shoe 16 passes over a track-ramp appertaining 15 to any road-signal which controls traffic in the opposite direction.

All the above described instrumentalities and operations are substantially as described in the specification of the co-pending application Serial No. 398,786 filed July 24th, 1920. The improved track layout will now be described which forms the subject of the present application, and which is adapted to permit of a locomotive being run backwards over a track-ramp without the brakes being in consequence applied, notwithstanding that the road signal with which such ramp co-operates is standing at "line blocked".

30 As will be seen on reference to the drawings, the track-ramp (which may be made a few feet longer than heretofore) comprises two sections 11 and 12 which are electrically insulated from one another at 35 13; the longer or "main" ramp-section 11 comprising the summit 14 and that end 15 of the ramp which is the first to be encountered by the plunger shoe 16 when the locomotive 17 passes over the ramp in the normal or forward direction of running as indicated by the arrow A; whilst the other section 12, hereinafter termed the "ramp extension," comprises that end 18 of the ramp which is the first to be encountered 40 by the plunger-shoe when a locomotive is backed over the ramp in the direction indicated by the arrow B. The main ramp-section 11 is electrically charged, during normal working, only when the road signal 45 19 stands at "line clear" (as in Figure 1), so that this section 11 is adapted normally to perform the functions of the undivided ramp hitherto employed, whereas the ramp-extension 12 is electrically charged only 50 when the signal 19 stands at "line blocked" (as in Figure 2), so that this section 12 is adapted to restrain the application of the brakes during the first part of the backward passage, over the ramp, of the plunger-shoe 16 on the locomotive; whilst means are provided for automatically causing the main ramp-section 11 to become electrically charged during the remainder of such backward passage of the plunger-shoe, and thus ensuring the continued re-

straint of the brakes throughout the entire backward movement of the locomotive 17 over the ramp.

For the purpose of transmitting current through the respective ramp-sections, two 70 independent electric batteries are employed, or the connections from a single source of current are so arranged as to produce an effect equivalent to that of such separate batteries. For the sake of convenience it 75 will hereinafter be assumed that two independent batteries 21 and 22 are provided, one for each ramp-section 11 and 12.

The battery 21 (hereinafter termed "the main ramp-battery"), which corresponds to 80 the usual single ramp-battery as regards the functions fulfilled in normal working, has one of its poles (say the positive pole) connected to the main ramp-section 11 through a pair of contacts 23, 24 which are 85 bridged by a switch 20 only when the signal 19 stands at "line clear," this (positive) pole being connected to earth through a pair of contacts 25, 26, which are bridged by the switch 20 only when the signal 90 stands at "line blocked." The opposite (i. e. negative) pole of the battery 21 is connected to earth through a pair of contacts 27, 28 which are bridged by a switch 29 only when the signal 95 19 stands at "line clear," and to the main ramp-section 11 through two switches in series with one another; that is to say, on the one hand through a pair of contacts 30, 31 which are bridged by the switch 29 only when the signal 19 stands at "line blocked," and on the other hand through a switch 32 so controlled by a stationary non-polarized relay 33 (which may be installed in the signal-cabin) as to be closed only when, the switch 29 being 100 already closed, the plunger shoe 16 of the locomotive 17 is being backed over the ramp.

The battery 22 (hereinafter termed the "ramp extension battery") has one of its poles (in the case assumed, the negative pole) permanently connected to the ramp-extension 12, whereas the opposite (i. e. positive) pole is connected to earth through the coil 37 of the non-polarized relay 33 and a pair of contacts 34, 35, which are 110 bridged by a switch 36 closed only when the signal 19 stands at "line blocked."

The connections appertaining to the two batteries are so arranged that whereas the ramp-extension battery 22 always has the same pole (in the case assumed, the negative pole) directly connected to the ramp-extension 12, the main ramp-battery 21 has its negative pole connected to the main ramp-section 11 (by way of the relay-switch 32) so long as the signal 19 stands at "line blocked," but has its positive pole connected to said main ramp-section 11 when the signal stands at "line clear." Hence the ramp-extension 12, which is elec- 120 125 130

trically alive only when the signal 19 stands at "line blocked," can in such circumstances transmit only current of negative polarity through the plunger shoe 16 and locomotive electro-magnet *s*, such current being prevented, by the locomotive polarized relay *u* from ringing the bell *w* in the cab. The main ramp-section 11 however is capable on the one hand of transmitting current of positive polarity through the plunger-shoe 16 and locomotive electro-magnet *s* when the signal 19 stands at "line clear," such current being permitted, by the locomotive polarized relay *u*, to ring the bell *w* in the cab; and is also capable on the other hand of transmitting current of negative polarity (by way of the relay-switch 32 if this be closed) when the signal 19 stands at "line blocked." 10

20 The stationary non-polarized relay 33 above mentioned has two windings 37 and 38 each of which is in circuit with one of the ramp sections 11, 12 and also independently capable, when energized, of effecting the closure of the relay-switch 32; the winding 37, which is in circuit with the ramp-extension 12, being interposed between the ramp-extension battery 22 and the contact 34 of the switch 36 whereby the positive 25 pole of said battery is earthed when the signal 19 stands at "line blocked;" whilst the winding 38, which is in circuit with the main ramp section 11, is interposed in the connection between said main ramp-section 30 and the closing contact 39 of the relay switch 32 itself. 35

The switches 20, 29 and 36 above referred to may be mechanically actuated and in the example illustrated are shown as operated by 40 means of the usual signal hand-lever 40 in the cabin; or they might be actuated by the signal-arm 19 itself, or by some part moving as one with either said arm or said hand-lever 40.

45 The length of the ramp-extension 12 should be limited to an end portion of the ramp so low as to be incapable, when the locomotive 17 is being backed over the ramp in the direction of the arrow B, of lifting the shoe 16 and plunger *a* on the locomotive to the height required for bringing about the application of the brakes.

In normal working, if the signal 19 is standing at "line clear," the plunger-shoe 16 of a 50 locomotive 17 which passes over the ramp in the forward direction (indicated by the arrow A) will find the main ramp-section 11 charged with current of positive polarity, so that current of this polarity will pass from the main ramp-battery 21 not only through the bell-circuit by way of the locomotive polarized relay *u*, thus causing the bell *w* to ring, but also through the locomotive electro-magnet *s*, thus energizing the latter and restraining the application of the brakes not- 55

withstanding that the plunger *a* is fully raised by the shoe 16 passing the summit 14 of the ramp. As the plunger shoe 16 thereafter passes forward, it finds the ramp-extension 12 electrically dead, so that the locomotive electromagnet *s* will cease to be energized; but, as the height of the ramp-extension 12 is insufficient for bringing about the operation of the brake-applying mechanism, the locomotive 17 will remain free to 60 travel forward clear of the ramp. 70

If, however, the signal 19 is standing at "line blocked," the plunger-shoe 16, on passing over the ramp in the forward direction, will find the main ramp-section 11 electrically dead, so that no current will pass either through the bell-circuit or through that of the locomotive electromagnet *s*, and hence the lifting of the plunger will be able to bring about the operation of the brake-applying mechanism. As the plunger-shoe 16 thereafter passes forward (unless the locomotive is already brought to rest) it finds the ramp-extension 12 electrically charged, but with current of negative polarity, so 75 that whilst the locomotive polarized relay *u* will prevent the bell *w* from being rung, the locomotive electromagnet *s* will be energized. This however, will not interfere with the application of the brakes which, when once applied, can only be released by the driver. The closing of the circuit of the ramp-extension battery 22 always causes the winding 37 of the stationary non-polarized relay 80 85 90 95 100 105 110 115 120 125 130 33 to be energized, but although this will result in the main ramp-section 11 becoming electrically charged in consequence of the closure of the relay-switch 32 so long as the plunger-shoe 16 remains in contact with the ramp-extension 12, the application of the brakes will not be interfered with, for the reason that the plunger-shoe 16 is no longer in contact with the main ramp-section 11. 100

If, now, the locomotive 17 should be backed over the ramp whilst the signal 19 is standing at "line blocked," the plunger-shoe 16 will find the ramp-extension 12 electrically charged with current of negative polarity, so that a negative current will pass through the circuit of the locomotive electromagnet *s*, the ramp-extension battery 22, and the winding 37 of the non-polarized relay 33. Hence, although the locomotive polarized relay *u* will prevent the bell from being rung, the locomotive electromagnet *s* will be energized and the plunger *a*, even if lifted high enough, will be prevented from bringing about the operation of the brake-applying mechanism. The closing of the circuit of the ramp-extension battery 22 causes the winding 37 of the relay 33 to be energized, so that the relay-switch 32 will be closed with the result that the main ramp-section 11 will be charged with current of negative polarity from the main ramp-battery 21. 130

Hence when the plunger-shoe 16 reaches the main ramp-section 11, the other winding 38 of the relay 33 will become energized by current from the main ramp-battery 21 and will continue to hold the relay-switch 32 closed notwithstanding that the winding 37 becomes de-energized on the plunger-shoe 16 passing out of contact with the ramp-extension 12. Therefore the energization of the locomotive electromagnet *s* will be maintained, and the plunger *a* will still be prevented from bringing about the operation of the brake-applying mechanism, so that the locomotive will be enabled to pass in the rearward direction clear of the ramp.

Having now particularly described and ascertained the nature of my said invention and in what manner the same is to be performed, I declare that what I claim is:—

1. In railway traffic-controlling apparatus the combination of a road signal, means for operating the same, a conductive shoe carried by a train, a track-ramp adapted to be engaged by said shoe and comprising a main ramp-section and a ramp-extension mutually insulated and so placed as to be respectively first encountered by said shoe as said train travels forward or backward and means co-operating with said signal operating means, whereby said main ramp-section alone is electrically charged when said road signal stands at "line clear" and whereby said ramp-extension alone is electrically charged when said signal stands at "line blocked" and whereby said main ramp section is electrically charged during the backward travel of said conductive shoe over it when said signal stands at "line blocked."

2. In railway traffic-controlling apparatus, the combination of a road signal, means for operating the same, a conductive shoe carried by a train, a track-ramp adapted to be engaged by said shoe and comprising a main ramp-section and a ramp-extension mutually insulated and so placed as to be respectively first encountered by said shoe as said train travels forward or backward, and electric means co-operating with said signal-operating means whereby, when the road signal stands at "line clear," said main ramp-section alone is charged with electric current of predetermined polarity, whereas, when the road signal stands at "line blocked," said ramp-extension alone is initially charged with current of the opposite polarity, whilst the main ramp-section is charged with current of said opposite polarity as a result of the train being backed over the ramp, substantially as set forth.

3. Railway traffic-controlling apparatus as claimed in claim 2, wherein two separate sources of electric current are provided, the ramp-extension being permanently connected with one pole of the one source of current, whilst the main ramp-section is adapt-

ed to be connected with the corresponding pole of the other source of current or with the opposite pole thereof, according as the road-signal stands at "line blocked" or "line clear."

4. In a railway traffic-controlling apparatus the combination of a road signal, means for operating the same, a conductive shoe carried by a train, a track-ramp adapted to be engaged by said shoe and comprising a main ramp-section and a ramp-extension mutually insulated and so placed as to be respectively first encountered by said shoe as said train travels forward or backward, two separate sources of electric current one pole of one of which is permanently connected with the ramp-extension, a relay having two windings in circuit respectively with the two ramp-sections, and switches controlled respectively by said relay and by the signal-operating means to cause the main-ramp-section to be connected with the corresponding pole of the other source of current or with the opposite pole thereof according as the road-signal stands at "line blocked" or "line clear."

5. The combination, with railway train-carried traffic-controlling apparatus of the known kind referred to and including a conductive movable shoe mounted on the train, of a road-signal installed beside the railway track, a track-ramp comprising two electrically-conductive and mutually insulated sections, namely, a main ramp-section and a ramp-extension so placed relatively to one another as to be respectively adapted to be first encountered by said shoe according as the train is travelling forward or backward, means for causing the main ramp-section alone to be electrically charged when the road signal with which the ramp is adapted to co-operate stands at "line clear," for causing the ramp-extension alone to be charged when said signal stands at "line blocked," and for automatically causing the main ramp-section to become charged during the backward passage of said conductive shoe over it when the signal stands at "line blocked," for the purpose set forth.

6. The combination, with railway train-carried traffic-controlling apparatus of the known kind referred to and including a conductive movable shoe mounted on the train, of a road-signal installed beside the railway track, a track-ramp comprising two electrically-conductive and mutually insulated sections, namely, a main ramp-section and a ramp-extension so placed relatively to one another as to be respectively adapted to be first encountered by said shoe according as the train is travelling forward or backward, means for causing the main ramp-section alone to be electrically charged when the road signal with which the ramp is

adapted to co-operate stands at "line clear," for causing the ramp-extension alone to be charged when said signal stands at "line blocked," and for automatically causing the 5 main ramp-section to become charged during the backward passage of said conductive shoe over it when the signal stands at "line blocked," said means comprising two separate sources of electric current, a non-polarized relay having two windings, switches whereof the condition is dependent upon the indication given by said road-signal, and electrical interconnections between said sources of current and the switches, the relay, and the sections of the ramp, substantially as and for the purpose set forth.

7. The combination, with railway train-carried traffic-controlling apparatus of the known kind referred to, of a track-ramp 20 comprising two mutually-insulated sections, a road-signal, electric batteries, a switch with a plurality of contacts, a second switch having a plurality of pairs of contacts, a third switch having a plurality of pairs of 25 contacts, means for controlling said switches in accordance with the indication given by the signal, a relay switch, a non-polarized relay having two windings and controlling

said relay switch, and electrical connections substantially as described.

8. In railway traffic-controlling apparatus, the combination of a track-ramp comprising a main ramp-section and a ramp-extension insulated therefrom, a road-signal, an operating lever therefor, a first electric battery, a second electric battery, a non-polarized relay having two windings and whereof one is connected through said second battery with the ramp-extension and the other winding is connected with the main ramp-section, a normally open switch controlled by said relay, a second switch controlled by the lever for earthing the ramp-extension through said second battery and said one winding when the signal stands at "line 45 blocked," and additional switches controlled by said lever for earthing the main ramp-section through said first battery in one direction when the signal stands at "line clear" and in the opposite direction through 50 said other winding and normally open switch when the latter is closed and said signal stands at "line blocked," substantially as described.

EDMUND SPENSER TIDDEMAN.
